UNITED STATES PATENT OFFICE.

CHARLES WALTER CASON, SR., OF CAMDEN, NEW JERSEY.

RAILROAD-TIE.

1,272,008.

Specification of Letters Patent.

Patented July 9, 1918.

Application filed November 2, 1917. Serial No. 199,936.

To all whom it may concern:

Be it known that I, CHARLES W. CASON, Sr., a citizen of the United States, residing at Camden, in the county of Camden and 5 State of New Jersey, have invented a new and useful Railroad-Tie, of which the following is a specification.

The subject of this invention is a tie intended for use on railroads, and the objects of the invention are, first, the provision of a tie formed of metal or like substance, second, the provision of means for quickly attaching a rail to and detaching it from a tie, third, the provision of a simple, durable and efficient tie.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, can be made within the scope of what is claimed, without 25 departing from the spirit of the invention.

A practical embodiment of the invention is shown in the accompanying drawing, wherein:

Figure 1 is a side elevation of the tie, a 30 part being in section;

Fig. 2 is a plan view;

Fig. 3 is a side elevation, partly in section, of a modified form.

Referring to the drawing by numerals of 35 reference:

The tie forming the subject of this invention consists of a base plate 1 from each side of both ends of which rise flanges 2 having inturned upper edges 3. Adjacent 40 each end of the tie and spaced from the inner ends of the flanges 2, is formed, preferably integral with the plate 1, a block 4 which is undercut transversely as at 5 to form a groove for the reception of one side 45 of the base flange 6 of a rail 7.

A block 8 is slidably mounted between the flanges 2 and has its inner end undercut, as at 9, to take over the other side of the base flange 6. The block 8 is provided with a 50 vertical aperture for the reception of a bolt 10 by which the block 8 is clamped in position to firmly bind the rail to the tie.

In the modified form shown in Fig. 3 the

base plate 1' has hollow boxings 2' formed at each end thereof, and a block 4' spaced 55 from the inner end of each boxing. Each block 4' is undercut as at 5' to receive the base flange 6 of the rail, while the inner end of each boxing 2' is undercut, as at 9' to receive the other side of the base flange 6. 60

A block 8' slides in each boxing 2' and has a rack 11 formed on its bottom edge which is engaged by a pinion 12 for the purpose of reciprocating the block to engage or release the web of the rail 7. 65

The ends of the base plate are thickened within the boxings 2', as shown, and the thickened parts are apertured or slotted as shown at 13, and within these slots the pinions 12 are mounted. 70

The pinions 12 are fixed on shafts 14, one of which extends transversely of each end, in which it is journaled. One end of each shaft 14 extends laterally beyond the tie and on this end is fixed a ratchet 15 which 75 is engaged by a pawl 16 for the purpose of locking the shaft to hold the block 8' firmly against the rail web. The pawl 16, as will be seen, is pivotally mounted on the side of the boxing 2'. 80

Any means, such as the wing head 17, may be secured to the end of each shaft 14 to permit of the same being rotated.

The foregoing description is thought to amply set forth the operation of the device 85 without a special explanation thereof.

Having thus described the invention, what is claimed as new and sought by Letters Patent, is:

A tie comprising a base plate, blocks rising from the base plate toward the ends thereof and adapted to engage the inner faces of parallel rails, a housing on each end of the base plate and spaced from the block, a rail contacting member slidable in 95 the housing, said member formed with a rack thereon, a pinion journaled in the base plate and engaging the rack, and means for locking the pinion against rotation. 90

In testimony that I claim the foregoing 100 as my own, I have hereto affixed my signature in the presence of two witnesses.

CHARLES WALTER CASON, SR.
